(57) **CLAIM**

The ornamental design for a milk froth machine, as shown and described.

DESCRIPTION

FIG. 1 is a perspective view of the milk froth machine of the invention;

FIG. 2 is a front view of the milk froth machine illustrated in FIG. 1;

FIG. 3 is a first side view of the milk froth machine illustrated in FIG. 1;

FIG. 4 is a second side view of the milk froth machine illustrated in FIG. 1;

FIG. 5 is a plan view of the milk froth machine illustrated in FIG. 1;

FIG. 6 is a bottom view of the milk froth machine illustrated in FIG. 1; and,

FIG. 7 is a rear view of the milk froth machine illustrated in FIG. 1.
